(57) **CLAIM**

The ornamental design for a container body portion, as shown and described.

DESCRIPTION

FIG. 1 is a perspective view of the container body portion looking downwardly from the front and right;

FIG. 2 is a top plan view of the container body portion; and, FIG. 3 is a front elevation view of the container body portion, the rear elevation view is the same.

The broken lines in the drawings are for illustrative purposes only and do not form a part of the claimed design.
